UNITED STATES PATENT OFFICE.

WILLIAM M. CLOW, OF WHEATLAND, ILLINOIS.

WIRE-FENCE NAIL.

SPECIFICATION forming part of Letters Patent No. 279,113, dated June 5, 1883.

Application filed February 27, 1883. (No model.)

To all whom it may concern:

Be it known that I, WILLIAM M. CLOW, of Wheatland, in Will county, and State of Illinois, have invented certain Improvements in 5 Wire-Fence Nails, the construction and operation of which I will proceed to explain, reference being had to the annexed drawings, making a part of this specification, in which—

Figure 1 is a side view, showing it applied 10 to two strand-wires and driven in the post; Fig. 2, an edge view, and Fig. 3 a perspective view.

This nail is for the purpose of holding two strand-wires of a wire or barbed-wire fence on 15 the post by being driven in between them, and so formed that its head projects each way over each wire, forming a hooked or hollowed head over each strand-wire, and having its head flared or widened at the upper end, so it may 20 be drawn from the post by an ordinary claw-hammer.

Referring to the drawings, *a'* represents the 25 nail proper, *a* the head, and *c c* the hollowed projections or shoulders for the purpose of holding the two strand-wires *w w*, as shown in Fig. 1. As shown in said figure, the nail is driven into the post between the two strand-wires *w w* in such manner that its hollow shoulders *c c* project out over the said strand-wires, 30 and hold the strand-wires firm on the post *P* after the nail has been driven home.

The head *a* of the nail projects above the 35 wire strands far enough so its flared upper end may be grasped by an ordinary claw-hammer, so the nail can be drawn from the post, when desired, and saved for use again or any number of times.

The hollow shoulders *c c* in this nail are not intended to continue over the strand-wires *w* so as to drive into the post, but only so far 40 as to inclose enough of the wires to hold them firm next the head of the nail.

I am aware nails of this character having one hook on one side to hold one wire or bar on the post have been used; but in such case 45 the head of the nail breaks off when driven home, because the head is not supported on either side, and it is useless in many instances. I am also aware a nail for this purpose has been in use having a pin through the head, so 50 that a claw-hammer can draw the nail by hooking under the pin; but in such case the pin has to be added to the nail after it is forged or cut, and the hole in which the pin sets weakens the 55 head, and in many cases the pin drops out and renders the nail incapable of being drawn. I am not aware of the use of a nail for this purpose having such a flared or widened head projecting some distance above the strand-wires for the purpose set forth. Neither am I aware 60 of the use of the double shoulders *c c*, formed as shown, to inclose and hold on two wires by being driven in between them.

Having thus described my invention, what I claim as new, and desire to secure by Letters 65 Patent, is as follows, to wit:

The wire-fence nail described, having the two projecting hollowed shoulders *c c* and flared head *a*, for the purpose set forth.

WILLIAM M. CLOW.
